UNITED STATES PATENT OFFICE.

LIVINGSTON ORRICK BENNETT, OF BALTIMORE, MARYLAND.

DUMPING-WAGON.

SPECIFICATION forming part of Letters Patent No. 334,633, dated January 19, 1886.

Application filed August 27, 1885. Serial No. 175,443. (No model.)

To all whom it may concern:

Be it known that I, LIVINGSTON O. BENNETT, of the city of Baltimore, and State of Maryland, have invented certain Improvements in Dumping Coal-Wagons, of which the following is a specification.

In the accompanying drawings, Figure I is an exterior side view of the improved coal-wagon. Fig. II is a front view of the same without the wheels. Fig. III is an exterior side view showing the body of the wagon extended and the hopper in two positions.

A is the hopper of the wagon, and B an extensible wheeled frame formed of the sections *a* and *b*. These sections *a* and *b* rest one upon the other, the one, *a*, being on top, and their extension and contraction are effected by means of a chain, *c*, chain-head *d*, sheave *e*, and suitable gearing adapted to operate the chain-head, as hereinafter fully described.

The chain passes around the chain-head *d* and the sheave *e*, which are on suitable shafts on the lower section, *b*, of the wheeled frame B, and is attached to the upper section, *a*, at *f*.

The rotation of the chain-head, whereby the upper section is drawn either forward or backward, is effected by the gear-wheel *g* and the pinion *h*, the latter being provided with a crank, *i*. The hopper A is supported directly by the upper section, *a*, of the frame, and is carried with it as the same is moved outward, (see Fig. III,) and when the frame is extended the overhanging section *a* is supported by the legs C C, which are preferably of the folding order, as shown in Fig. III. I do not limit myself, however, to the particular description of supports shown for sustaining the section

a of the frame, as various other devices could be employed for the purpose.

D D are standards on the section *a* of the frame B, having sheaves *k* at their upper ends. Chains *l* extend from winding devices E over the sheaves *k* to the ends of levers F, which have their fulcra at *m* on the upper section of the frame. The levers F are connected to the hopper A by means of pivotal bolts *n*, consequently when the said levers are raised by means of the chains *l* the hopper is carried with them. (See Fig. III.) The desired inclination of the hopper is effected by the secondary levers G, pivoted to the hopper at *o* and to the frame at *p*. The winding-drums E are on a shaft, *q*, which is revolved through the medium of the gears *r* and *s* and the crank *t*.

H H are segmental guide-bars for the levers F, two of which are attached to each of the standards D, to support them from the section *a* of the wheeled frame. The levers F are situated between the guide-bars, as shown in Fig. II.

I claim as my invention—

In a dumping-wagon, the frame B, formed of the upper and lower sections, *a* and *b*, arranged to be extensible, as described, hopper A, and levers F and G, pivoted to the hopper A and the section *a*, combined with the standards D, and a chain and winding apparatus, whereby the hopper can be elevated and tilted at one operation, substantially as specified.

LIVINGSTON ORRICK BENNETT.
